UNITED STATES PATENT OFFICE.

HOWARD J. KELLEY AND CHARLES H. GARRETT, JR., OF KANSAS CITY, MISSOURI;
SAID GARRETT ASSIGNOR TO SAID KELLEY.

DESIGN FOR AN AEROPLANE.

50,912.

Specification for Design. Patented June 12, 1917.

Application filed June 21, 1915. Serial No. 35,459. Term of patent 7 years.

To all whom it may concern:

Be it known that we, HOWARD J. KELLEY and CHARLES H. GARRETT, Jr., citizens of the United States, residing at Kansas City, in the county of Jackson and State of Missouri, have invented a new, original, and ornamental Design for Aeroplanes, of which the following is a specification, reference being had to the accompanying drawing, in which—

Figure 1 is a plan view of an aeroplane showing our design.

Fig. 2 is a side elevation of the design.

Fig. 3 is a rear elevation of the design.

We claim:

The ornamental design for an aeroplane, as shown.

HOWARD J. KELLEY.
CHARLES H. GARRETT, JR.
